WEIGHING SCALE

John Watling, Oak Park, Ill., assignor to Watling Scale Company, Chicago, Ill., a corporation of Illinois

Application September 4, 1958, Serial No. 52,499

Term of patent 14 years

(Cl. D52—10)

Fig. 1.

Fig. 2.

Figure 1 is a perspective view of a weighing scale embodying my new design; and

Figure 2 is a side elevational view thereof, taken from the right of Figure 1.

The undisclosed side of the weighing scale is substantially the same in appearance as the side shown, and the rear is plain.

I claim:

The ornamental design for a weighing scale, substantially as shown and described.
